The ornamental design for a scalp applicator, as shown and described.

CLAIM

FIG. 1 is a perspective view of an scalp applicator, embodying our new design;

FIG. 2 is a top view thereof;

FIG. 3 is a bottom view thereof;

FIG. 4 is a right side elevational view thereof; the left side being a mirror image;

FIG. 5 is a rear elevational view thereof; and,

FIG. 6 is a front elevational view thereof.

The broken lines in the drawings are for illustrative purposes only and do not form part of the claimed design.
